RAILWAY CAR

Peter Parke, Chicago, Ill., assignor to The Pullman Company, Chicago, Ill., a corporation of Illinois

Application February 15, 1940, Serial No. 319,089

6 Claims. (Cl. 105—315)

This invention relates to railway sleeping cars and has particular reference to a new Pullman de luxe accommodation known as the Master Room and has for its principal object the provision of a spacious room having concealed sleeping accommodations comprising beds foldable endwise at right angles into the walls of the room with movable chairs for use when the beds are closed and adapted to be folded for storage under the beds during use of the beds. An important feature of the invention is the location of the master room between an adjoining communicable bedroom and an adjoining toilet and bath whereby the two rooms may be used en suite and the bath then available to the occupants of either.

The foregoing and other and more specific objects of the invention are attained by the construction illustrated in the accompanying drawings in which—

Fig. 1 is a general perspective view of a railway car having parts broken away to reveal the general arrangement of the room of this invention with its adjoining bathroom and the communicating bedroom with all of the facilities disposed for daytime use and the folding partition between the rooms in open position;

Fig. 2 is also a general perspective view of the rooms with the beds made up for nighttime occupancy and the folding partition between the rooms in the closed position;

Fig. 3 is a general plan view of the room arrangement with all facilities disposed for daytime use;

Fig. 4 is a longitudinal, sectional view through the rooms, taken on the line 4—4 of Fig. 3, looking towards the side wall with the beds made up for nighttime occupancy;

Fig. 5 is a longitudinal, sectional view through the rooms, taken on the line 5—5 of Fig. 3, looking towards the aisle partition with the beds in their closed daytime positions;

Fig. 6 is a vertical, cross-sectional view through the adjoining bedroom, taken on the line 6—6 of Fig. 3, showing the sofa-bed and upper berth in closed position;

Fig. 7 is a vertical, cross-sectional view through the adjoining bedroom, taken on the line 7—7 of Fig. 3, showing the enclosed toilet facilities and folding partition;

Fig. 8 is a vertical, cross-sectional view through the master room, taken on the line 8—8 of Fig. 3, showing the transversely disposed folding bed in open position adjacent to the folding partition;

Fig. 9 is a vertical, cross-sectional view through the master room, taken on the line 9—9 of Fig. 3, 55

showing the longitudinally disposed folding bed in the closed position and the entrance door to the bathroom; and

Fig. 10 is a vertical, cross-sectional view through the bathroom taken on the line 10—10 of Fig. 3.

In the drawings, 10 represents a railway car having an aisle 11 and a master room 12. The master room is formed by aisle partition 15 and side wall 16 connected by folding partition 13 and fixed partition 14, and it will be noted that each of such walls and partitions is disposed in a single plane, wherefore it may be said that the room is formed by rectilinear walls. Ceilings 17, in the master room, and 18, in the aisle, provide 15 roof zones above the master room and aisle, respectively, for a purpose hereinafter to appear. An entrance door 19, disposed in the aisle partition 15, provides access to the master room from the aisle, and a mirror 20, on the inner side of 20 the door, adds to the convenience of the occupants of the room. The folding partition 13 permits of the use of adjoining rooms en suite, and a mirror 22 is provided thereon in the adjoining room hereinafter to be described and which may be duplicated upon opposite sides of the partition, if desired. Disposed in the fixed partition 14 opposite the folding partition, a door 21 provides access to an adjoining private toilet and bath 32.

30 The bathroom 32 contains all of the toilet facilities for the room—including a medicine cabinet 23, a washstand 24, a hopper 26 and a shower tub 25. The medicine cabinet is provided with a hinged door 27, having a mirror 28, and is adapted for the accommodation of toilet articles. An exterior shelf 30 may be used for the accommodation of toilet articles while the mirror 28 is being used. The washstand 24 is disposed beneath the medicine cabinet and is provided with hot and cold water faucets 38 connected with concealed supply pipes (not shown) and with a drain (not shown) emptying beneath the car. The hopper 26 is provided with a hinged seat 35 and a cover 36 and, as best shown in Figs. 1 and 3, 35 is disposed in a corner of the bathroom adjacent the side wall of the car and out of the way of the washstand and medicine cabinet. A window 29 is provided in the bathroom to admit light and is disposed in the side wall 16. The shower tub 25 is disposed upon the opposite side of the bathroom entrance door 21 from the toilet and washstand and is provided with a shower curtain 33 supported from rod 34—affording an enclosable stall—and is equipped with a shower head 37 having controls 39 for regulating the flow of

water therethrough. A drain 31 is provided in the shower tub to empty waste water beneath the car.

In the master room, between the doors 19 and 21 and disposed adjacent the aisle partition 15 and partition 14 in the corner formed thereby, is a dual wardrobe 45 for the convenience of the occupants of the room. Dividing-partition 46 separates the wardrobe into individual compartments accessible through twin doors 41. A baggage shelf 40 is disposed at the top of the wardrobes and extends the length of the aisle partition 15 and along the bathroom partition 14 above the door 21. On the opposite side of the bathroom door 21 from the wardrobe 45, the partition 14 is constructed of greater depth, as at 111, in order to accommodate a folding bed 112 hingedly mounted therein, at 113, and foldable endwise flush therewithin, as best shown in Figs. 1, 3 and 9. The hinge point 113 is disposed adjacent to the lower end of the bed in the vertical, closed position; and the bed is movable thereabout from the fully closed position indicated in dotted lines in Fig. 4 to the full-open, horizontal position indicated in full lines in this same figure, during which movement the bed is balanced for easy handling by coil springs 114 arranged in batteries of three at each side of the bed, as shown in Fig. 9, and anchored to angle members 115 and 116 rigidly secured to the lower end of the bed and the car floor, respectively. The bed 112 is received in recess 117 in the closed position and releasably secured by spring-actuated catches 118 mounted in the respective side walls of the recess and engageable with complementary combination lock member castings 119 secured in respectively opposing side walls of the bed. The latches 118 each engage the respective castings to hold the bed closed and are released, when it is desired to lower the bed, by means of push rods 121 which engage the latches and depress them from engagement with the castings and hold them depressed until the bed is moved to a position beyond which the latches cannot engage the castings 119. The push rods 121 are projected in opposite directions by means of eccentric 126 operated by handle 125 exposed on the face of the bed in the closed position thereof convenient for use. The combination lock member castings also serve a further, useful function in the open position of the bed as hereinafter described.

In the open position, the bed, at its edge away from the wall 16, is supported from the floor by means of a combination bed leg and mattress holder 127 hingedly mounted on the side wall of the bed at the top edge thereof, as at 128, and adapted to swing, through an arc of 270° or more, from a position clamping the mattress, in the vertical, closed position of the bed, to a position supporting the bed in its horizontal, open position. The bed leg is provided with a catch 129 engageable with the casting 119 to hold the leg vertical and closely adjacent to the side of the bed in supporting position and to prevent the foot of the leg from being displaced outwardly. When it is desired to close the bed, the leg 127 may be swung to lie across the mattress 133 where it is adapted to be secured to hold the mattress in place as the bed is raised to its vertical, closed position.

At its edge adjacent to wall 16, the bed is supported in its open, horizontal position by means of combined bed support and holder 145 which also prevents the bed from accidentally closing

under the influence of springs 114 combined with starting or stopping movements of the car. The member 145 is provided with a supporting member 146 pivotally mounted therein and normally flush with the surface thereof in the closed position, but which is movable to an extended, horizontal position before the bed is lowered to its horizontal position of rest thereon. Bearing plate 148, secured to the bed 112, prevents scuffing of the finish on the face of the bed from contact with the support 146. The support, in its extended position, finds bearing in the member 145 at opposite sides of its pivot point and is held in its respectively opposite extended and closed positions by a coil spring mounted to exert a thrust beyond dead center with respect to the pivot point in each of the two such extreme positions. The support 146 is channel-shaped in cross-section and, in the closed position, is adapted, through the force exerted beyond dead center in this position, to confine a spring-actuated bed hold-down device 155 operating in conjunction therewith. The support and holding device both are disposed flush with the surface of member 145 and are adapted, both, to move outwardly into operative positions when the support member is moved to a position where its spring exerts pressure beyond dead center outwardly—thus urging such member to full open, supporting position and releasing the hold-down device to move to bed-holding position under influence of its own spring. The bed-holding device 155 is pivotally mounted in the member 145, and the actuating spring therefor operates in torsion about the pivot point. Stops are provided for limiting outward movement of the holding device.

In the open position, the bed-holding device is adapted to project into the path of movement of the bed 112, whereby, as the bed is lowered onto the support 146, it will automatically engage the casting 119 on the wall-adjacent side of the bed. It will readily be seen that the device 155 acts as a strut between the casting 119 on the bed and its pivot point on the wall, thereby preventing upward movement of the bed and keeping the bed from closing or being closed without first releasing the holding device. When it is desired to close the bed 112, the catch 129 is released and the leg 127 secured across the mattress 133 and the holding device then released, whereupon the bed may be raised to its vertical position within recess 117 and secured by catches 118, after which the holding device 155 is pressed into the member 145 and the support 146 closed thereabout to hold it in place and provide a flush surface. A safety device is provided in the closed position of the bed to prevent the bed from falling accidentally in the event that the concealed catches 118 are not fully and positively engaged. An automatically operating, spring-actuated catch 165 is disposed above and in position to be engaged by the bed as it is closed and provides a safety device, fully exposed to view, which must be operated by a porter with a stick having a hook on the end, provided for the purpose, before the bed can be released.

As best shown in Fig. 2, the master room is provided with beds at right angles to each other and both of which are foldable endwise into recesses in respectively adjacent, angularly disposed walls thereof and, as shown, are arranged in diagonally opposite corners of the rooms. The bed above described is foldable into the partition 14 adjacent to the side wall 16 of the car and is

openable to a longitudinally disposed position along the side wall beneath the windows 14, but does not extend the full length of the room. At the diagonally opposite corner of the room from the bed first described, the aisle partition 15 is constructed of greater depth, as at 111^a, in order to accommodate a folding bed 112^a hingedly mounted therein at 113^a and foldable endwise flush therewith, as best shown in Figs. 1, 3 and 5. The hinge point 113^a is disposed adjacent to the lower end of the bed in the vertical position thereof, and the bed is movable thereabout from the fully closed position indicated in dotted lines in Fig. 8 to the full-open, horizontal position indicated in full lines in this same figure, during which movement the bed is balanced for easy handling by coil springs 114^a as shown in Fig. 5. In its open, horizontal position, the bed 112^a is disposed transversely of the car and of the room and extends across the folding partition 13 between the foot of the bed 112 and the partition and, of course, is arranged to operate in a plane at right angles to the plane of operation of the bed 112. In its vertical, closed position, the bed 112^a is received in recess 117^a and releasably secured by spring-actuated catches 118^a mounted in the side walls of the recess in positions to engage complementary combination lock member castings 119^a in the opposite side walls of the bed. When it is desired to lower the bed to open position, the latches 118^a are released by means of push rods 121^a which are adapted to press the latches from engagement with the castings 119^a so that the bed may be removed from the recess 117^a. The push rods 121^a are projected in opposite directions by means of eccentric 128^a operated by handle 129^a on the face of the bed.

The bed 112^a, at its edge away from the partition 13, is supported in the open position from the floor by means of a combination bed leg and mattress holder 127^a hingedly mounted on the side wall of the bed and adapted releasably to engage the lock casting 119^a to hold the leg in bed-supporting position. The leg also may be secured across the mattress 133^a to hold the bedding in place in the vertical, closed position of the bed. At its edge next to partition 13, the bed is supported from a fixed panel 13^a forming part of the partition by means of a combined bed support and holder 145^a. A bed-supporting member 146^a is pivotally mounted in the member 145^a normally flush therewith and is adapted to be moved to an extended horizontal position before the bed is lowered to rest thereon. The member 146^a also incorporates a bed hold-down device 155^a operating in conjunction with the supporting member 146^a and both of which are spring-actuated and function in exactly the same manner as the similar support hereinbefore described for use with the bed 112. The bed 112^a is also provided with a safety device 165^a disposed above the bed recess on the aisle partition 111^a in position to be engaged by the bed as it reaches closed position and which is releasable manually and functions, generally, similarly to the device 165 for the bed 112.

The master room may not be used en suite with the adjoining room when the bed 112^a is made up, since the folding partition 13 is then traversed by the bed. By disposing folding beds for operation in planes at right angles to each other, greater spaciousness is thereby given the room and a larger floor area is rendered available when the beds are made up, at which time the occupant of either bed may have access to any

of the other facilities of the accommodation without disturbing the other occupant; and, by arranging the beds in the particular manner disclosed, at diagonally opposite corners of the room, greater window area is afforded. Movable chairs 93 are utilized for daytime use which are capable of being folded, and at night, when not in use, are collapsed and stored under the beds. The utility and spaciousness of the room arrangement is readily apparent from an inspection of Figs. 1 and 2, wherein it will be seen that the full area of the room is available when the beds are closed, and all of the facilities of the room are disposed for most convenient use regardless of the positions of the beds.

The adjoining bedroom 120, which may be used en suite with the master room 12 by folding back the partition 13 as shown in Fig. 1, is equipped with a convertible sofa-bed 122 disposed transversely of the room which may be utilized by the occupants of either room when the en suite arrangement is availed of. The sofa 122 is convertible into a bed for use of an occupant of the bedroom, and an upper berth 123 is provided to afford an additional sleeping accommodation for this room. A fixture 124, combining an enclosed toilet hopper, folding washstand and medicine cabinet, is provided in the bedroom for use of the occupants thereof at times when this room is used singly; but when the rooms are used en suite, the bathroom 32 is available to the occupants of either room. Window 130 is provided in the bedroom, and entrance door 131 affords access thereto independently of the master room.

The roof zone space above the aisle ceiling 18 is utilized for the accommodation of conditioned air duct 100 which opens into the master room, the bedroom and the bathroom through suitable outlets 101, 135 and branch connection 107, respectively. The outlets 101 and 135 each have an extended, perforated surface 103 and 136 enclosing respective pressure chambers 102 and 137, which causes even admission of air throughout the surface area of the outlets and equal distribution of fresh air to the rooms. The fresh air supplied to the bathroom 32 by means of branch connection 107 is admitted through the ceiling thereof. Outlet grille 104 in the master room entrance door 19 and grille 147 in the bedroom entrance door 131 provide for recirculation of air in the rooms through the aisle area 11—the air withdrawn from the rooms entering a recirculated air inlet (not shown) disposed in the ceiling 18 to air conditioning equipment (not shown) in the roof zone of the car at one end for redistribution to the car interior. Outlet grille 108, in the bathroom door 21, provides air communication with the master room. The roof zone area above the ceiling over the rooms accommodates a vitiated air duct 105 communicating with the various rooms by means of ceiling inlets 106 in the master room, 149 in the bedroom, and 110 in the bathroom for exhausting foul and smoke-laden air to the atmosphere, and which may be regulated to control the amount of air withdrawn by blower equipment (not shown) connected with the duct and disposed at the opposite end of the car from that containing the air conditioning equipment above referred to. A branch duct 105 connects the grille 110 in the bathroom with the main duct 105 for communication therewith to withdraw vitiated air from this room.

From the foregoing, it will be seen that a new and luxurious Pullman accommodation has been

provided in which beds, foldable endwise and arranged for operation in planes at right angles, afford full utilization of the entire floor area of the room and, so disposed, permit the most convenient use of the remaining facilities of the room.

Reference is herein made to copending applications (Serial No. 276,438, filed May 29, 1939; Serial No. 282,109, filed June 30, 1939; and Serial No. 288,294, filed August 4, 1939) for further information in regard to more specific details of construction with respect to the beds and their appurtenances and the bedroom arrangement and folding partition details.

What is claimed is:

1. In a railway car having a side wall and a straight parallel aisle wall, a pair of straight, fixed partitions and an intermediate folding partition all parallel to each other and connecting the side and aisle walls and defining a pair of adjacent rooms divided by the intermediate partition and adapted to be used en suite when the intermediate partition is folded, a sofa adjacent one of the fixed partitions and extending transversely of the car, a door in the aisle wall between the sofa and the folding partition, a pair of folding beds between the folding partition and the other fixed partition, said beds being disposed right-angularly to each other when extended and one of them being foldable endwise into the aisle wall and extensible along the folding partition and adjacent thereto, and a door in the aisle wall between the last named bed and the second named fixed partition.

2. In a railway car having a side wall and a straight parallel aisle wall, a pair of straight, fixed partitions and an intermediate partition all parallel to each other and connecting the side and aisle walls and defining a pair of adjacent rooms divided by the intermediate partition, said intermediate partition comprising a portion fixed to the side wall and a portion foldable against the aisle wall and said rooms being adapted to be used en suite when the foldable portion of the intermediate partition is in folded position, a sofa adjacent one of the fixed partitions and extending transversely of the car, a door in the aisle wall between the sofa and the intermediate partition, a pair of folding beds between the intermediate partition and the other fixed partition, said beds being disposed right-angularly to each other when extended and one of them being foldable endwise into the aisle wall and extensible along the intermediate partition and adjacent thereto, means carried by the fixed portion of the intermediate partition for supporting the extended end portion of the last named bed, and a door in the aisle wall between the last named bed and the second named fixed partition.

3. In a railway car having a side wall and a straight parallel aisle wall, a pair of straight, fixed partitions and an intermediate partition all parallel to each other and connecting the side and aisle walls and defining a pair of adjacent rooms divided by the intermediate partition, said intermediate partition comprising a portion fixed to the side wall and a portion foldable against the aisle wall and said rooms being adapted to be used en suite when the foldable portion of the intermediate partition is in folded position, a sofa adjacent one of the fixed partitions and extending transversely of the car, a door in the aisle wall between the sofa and the intermediate partition, a folding bed between

the intermediate position and the other fixed partition, said bed being foldable endwise into the aisle wall and extensible along the intermediate partition and adjacent thereto, means for supporting the free end of said bed in extended position comprising a bracket carried by the fixed portion of the intermediate partition and adapted to support one side of the bed and a foldable leg mounted on and adapted to support the other side of the bed, and a door in the aisle wall between said bed and the second named fixed partition.

4. In a railway car having a side wall and a straight parallel aisle wall, a pair of straight, fixed partitions and an intermediate partition all parallel to each other and connecting the side and aisle walls and defining a pair of adjacent rooms divided by the intermediate partition, said intermediate partition comprising a portion fixed to the side wall and a portion foldable against the aisle wall and said rooms being adapted to be used en suite when the foldable portion of the intermediate partition is in folded position, a sofa adjacent one of the fixed partitions and extending transversely of the car, a door in the aisle wall between the sofa and the intermediate partition, a pair of folding beds between the intermediate partition and the other fixed partition including a bed foldable endwise into said other fixed partition and extensible longitudinally of the car to a position parallel to and adjacent the side wall and a bed foldable endwise into the aisle wall and extensible along the intermediate partition and adjacent thereto, means for supporting the free end of the first named bed in extended position comprising a bracket carried by the side wall and adapted to support one side of the bed and a foldable leg mounted on and adapted to support the other side of the bed, means for supporting the free end of the second named bed in extended position comprising a bracket carried by the fixed portion of the intermediate partition and adapted to support one side of the bed and a foldable leg mounted on and adapted to support the other side of the bed, and a door in the aisle wall between said bed and the second named fixed partition.

5. In a railway car, a master room having a bed therein disposed transversely of the car and a second bed disposed longitudinally of the car adjacent to the car side wall, a bed room adjoining the master room at one end having sleeping accommodations and toilet facilities and separated from the master room by a folding partition extending substantially entirely across the two rooms and adapted when folded to convert said two rooms into a single large room, said transverse bed being disposed adjacent to the folding partition and being foldable off the floor area against one of the room walls extending longitudinally of the car, said longitudinal bed being foldable off of the floor area and against the room wall opposite to the folding partition, a bath room adjoining the master room at the other end and separated therefrom by a fixed partition having a door whereby the facilities of the bath room are available to the occupants of said single large room when the folding partition is folded, an aisle wall defining one side of the master room, bed room and bath room, and separate doors in the aisle wall opening into the master room and the bed room, the latter door being covered by the folding partition when in folded position.

6. In a railway car, a master room, a bed room adjoining the master room at one end having sleeping accommodations and toilet facilities and separated from the master room by a folding partition extending substantially entirely across the two rooms and adapted when folded to convert said two rooms into a single large room, a bath room adjoining the master room at the other end and separated therefrom by a fixed partition having a door whereby the facilities of the bath room are available to the occupants of said single large room when the folding partition is folded, a side wall and

5 an aisle wall defining opposite sides of the master room, bed room and bath room, separate doors in the aisle wall opening into the master room and the bed room, the latter door being covered by the folding partition when in folded position, a bed in the master room foldable into the fixed partition between the door therein and the side wall and extensible along the side wall, and a second bed in the master room extending transversely of the car adjacent to the folding partition and foldable against the aisle wall.

PETER PARKE.
